ROTATABLE STORAGE AND DISPLAY STAND
FOR TAPE OR FILM CARTRIDGES OR THE
LIKE

Henry V. Ivory, Chatham, N.J., assignor to
Boorum & Pease Company, Brooklyn, N.Y.

Filed Nov. 3, 1969, Ser. No. 19,906

Term of patent 14 years

Int. Cl. D6—01

U.S. Cl. D80—10

FIG. 2

FIG. 1

FIG. 1 is an elevational view of a rotatable storage and display stand for tape or film cartridges or the like showing my new design.

FIG. 2 is a top plan view thereof.

FIG. 3 is an exploded perspective view thereof.

The broken line representation of a cartridge in FIG. 1 is for illustrative purposes.

I claim:

The ornamental design for a rotatable storage and display stand for tape or film cartridges or the like, as shown and described.
